(57) **CLAIM**

The ornamental design for a power or control module for furniture as shown and described.

DESCRIPTION

FIG. 1 is a perspective view of a first embodiment of a power or control module for furniture showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of a power or control module for furniture showing my new design;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a perspective view of a third embodiment of a power or control module for furniture showing my new design;

FIG. 16 is a front view thereof;

FIG. 17 is a rear view thereof;

FIG. 18 is a right side view thereof;

FIG. 19 is a left side view thereof;

FIG. 20 is a top view thereof;

FIG. 21 is a bottom view thereof; and,

FIG. 22 is an alternate perspective view showing an unclaimed mounting bracket and power cord.

The greyscale shading shown in FIGS. 1-22 is provided solely for the purpose of showing surface contours and does not indicate a particular color. The dash-dot lines in FIGS. 1-22 and the areas within the dash-dot lines shown in

(Continued)

phantom show portions of the power or control module for furniture that form no part of the claimed design.
